UNITED STATES PATENT OFFICE.

BERNARD H. SKELLY, OF BRIDGEPORT, CONNECTICUT, ASSIGNOR TO AMERICAN SPECIALTY CO., INC., OF BRIDGEPORT, CONNECTICUT, A CORPORATION OF CONNECTICUT.

VACUUM-TUBE MOUNTING FOR RADIO APPARATUS.

Application filed June 26, 1926. Serial No. 118,688.

This invention has reference to the vacuum tubes used in radio apparatus, but more particularly relates to the mounting of said tubes in such manner that they are capable of oscillation so as to be shock absorbing.

The main object of this invention is to so mount these tubes that they can be selectively utilized as vibratory or stationary tubes at the will of the operator.

In the accompanying drawing—

Figure 1 is an elevation of the assembled device in perspective—

Figure 2 a detail side elevation of the vacuum tube—

Figure 3 is a plan view of the device with the tube removed—

Figure 4 is a section at the line 4—4 with the screw relaxed—

Figure 5 is a similar section with the screw tightened—

Figure 6 is a bottom view of the base—

Figure 7 is a perspective of the base with platform removed, and

Figure 8 is a bottom view of the platform.

Tubes of this description that are vibratory so as to be shock absorbing are well known, and, under some circumstances possess advantages, but these tubes are generally stationary, since, under most conditions, stationary tubes are preferable, and since it is quite expensive and confusing to keep two sets of tubes on hand, and to use them alternately, as conditions change, the present style of tube mounting has been devised, so that the same tube can in an instant be converted from a vibratory to a stationary tube and vice versa, and the invention will be readily understood from the following description, reference being had to the accompanying drawing, similar numerals being used to designate like parts in the several figures.

1 is a base of any suitable insulating material, and 2 the wiring terminals mounted on said base and connected with upwardly extending resilient contacts 3 for engaging the electrodes of a vacuum tube 4, these electrodes comprising pins 5, 6, the pins 5 being preferably larger than the pins 6 for the purpose presently explained.

7 is a platform of insulating material for supporting the tube and formed with comparatively large perforations 8 and com-

paratively small perforations 9 through 12, which the large and small pins 5, 6, are inserted in the mounting of the tube on said platform, and these perforations lead into enlarged recesses 10 into which the contacts 3 are inserted when the platform is assembled relatively to the base.

These contacts at their upper ends have resilient offsets 11 which normally extend in the vertical planes of the perforations 8, 9, so as to be within the path of the pins 5, 6, when the latter are mounted on the platform, so that it will be clear that these pin electrodes will have good contact with the wiring terminals 2.

Also, when the platform is assembled on the base, the upper walls of the recesses 10 will rest on these contacts 3 so that it will be evident that the platform and its tube will be oscillatory.

Extending through the centers of the platform and base are aligned perforations 12, 13, the latter having an interiorly threaded bushing 14, and a screw 15 passed loosely through the perforation 12 is driven into the bushing 14, whereby the platform and base are secured in their assembly, and this screw may be driven into the bushing more or less so as to vary the tension on the resilient contacts and consequently the delicacy of the vibratory motions of the platform and tube.

When it is desired to convert the oscillatory tube into a stationary tube, the screw is driven so as to bind the platform against the base in opposition to the resiliency of the spring contacts, but the relaxation of the screw will instantly transform the rigid tube into an oscillatory tube, since the recovery of the spring contacts will separate the platform and base.

In order to aid these contacts I prefer to employ a coil spring 16 which surrounds the screw and is housed within a recess 17 in the bottom of the platform, and which is compressed when the screw is driven into the bushing 14, and which, therefore, acts to separate the platform and the base when the screw is relaxed, and also contributes toward the resilient supporting of the platform.

This coil spring may be omitted, if desired, and although I prefer to use it, the invention is not to be limited thereby.

In order that the electrodes of the vacuum tube may engage the proper spring contacts,

two of these electrodes are larger than the other two, and the corresponding perforations in the platform are made to accommodate these comparatively large and small pins, so that it will be impossible to improperly assemble tubes on the platform, this being an ordinary expedient.

What is claimed is:—

1. In a vacuum tube mounting, an insulated base having wiring terminals provided with upstanding resilient contacts, a platform supported by said contacts, and adjustable means for spacing apart said platform and base or for securing them rigidly together, whereby said mounting may be selectively vibratory or stationary.

2. In a vacuum tube mounting, an insulated platform, an insulated base, resilient contacts carried by the base and on which said platform is mounted, and a screw extending loosely through said platform and having a threaded engagement with said base, whereby said base and platform may be rigidly bound together or may be held in as-

sembly with the platform supported for oscillatory movements.

3. In a vacuum tube mounting, an insulated base having wiring terminals provided with upstanding resilient contacts, a platform, a coil spring interposed between said base and platform, and adjustable means for spacing apart said platform and base or for rigidly securing them together, whereby said platform may be selectively vibratory or stationary.

4. In a vacuum tube mounting, an insulated base having wiring terminals provided with upstanding resilient contacts, a platform, resilient means interposed between said platform and base, and adjustable means for spacing apart said platform and base or for securing them rigidly together, whereby said platform may be selectively vibratory or stationary.

In testimony whereof I affix my signature hereto.

BERNARD H. SKELLY
